Claims priority, application Germany, Sept. 22, 1962,
R 33,548

16 Claims. (Cl. 102—70)

The present invention relates to a detonator mechanism.

More particularly, the present invention relates to a detonator mechanism which is of the type that explodes the charge when a weight or load resting on the mechanism is removed.

Detonators of the above type are well known. They generally comprise a firing pin which explodes the charge, as well as a locking device which itself is under spring tension and which prevents the firing pin from striking the primer. The arrangement is generally such that in the "safe" condition of the detonator, the locking means are held, by means of a clock mechanism, in a position in which the locking means prevent movement of the firing pin, while in the "armed" condition, it is the weight resting on the locking means which holds the locking means in the position in which movement of the firing pin is prevented.

Experience has shown that conventional detonators of the above type are relatively complicated, expensive, and subject to malfunction, and it is, therefore, a primary object of the present invention to provide a detonator mechanism of the above-described general type, which detonator mechanism, however, overcomes the mentioned drawbacks. According to the present invention, this is accomplished by arranging the locking means centrally, or substantially centrally, of the housing, and by arranging the clock mechanism radially with respect to the locking means, the clock mechanism being provided with a slide element which coacts with a locking projection of the locking means.

Additional objects and advantages of the present invention will become apparent upon consideration of the following description when taken in conjunction with the accompanying drawings in which:

FIGURE 1 is a cross-sectional view of one embodiment of a detonator mechanism according to the present invention, taken on line 1—1 of FIGURE 2.

FIGURE 2 is a top plan view of the detonator mechanism of FIGURE 1, but without the cover.

FIGURE 3 is a cross-sectional view of another embodiment of a detonator mechanism according to the present invention.

FIGURE 4 is a top sectional view taken on line 4—4 of FIGURE 3.

Referring now to the drawings and to FIGURES 1 and 2 thereof in particular, the same show a release-type detonator comprising a substantially annular housing 1 made of a plastic material and provided with an integral web extending diametrically through the housing. The top and bottom of the housing are closed off by covers 2 and 3. Arranged within a suitably configured and preferably rectangular recess in the web is a clock mechanism 4, the same having a winding stem 4a passing upwardly through the cover 2, and locking slide 4b. The clock mechanism is held in place by means of screws 5. The covers 2 and 3 are held in place by means of screws (not shown) which are screwed into threaded bores 6 of the housing 1. A lever 7, which is made, for example, of stamped sheet metal and which is pivotally attached to the housing 1 by means of a pin 10, coacts

2

with the locking slide 4b. This lever 7 is provided with a blocking element in the form of a lug 7a, a locking projection 7b, and a head 7c. The head 7c extends through an opening of the cover 2, which opening is tightly sealed by means of a membrane 8 made, for example, of rubber. Located above the head 7 and on the other side of the membrane 8 is a plate 9.

The web of the housing is provided with a cylindrical and stepped recess which is closed off by means of a screw ring 11 and a spacer ring 12. Arranged within this recess is a primer charge assembly incorporating a primer charge 13 of nitropenta or other suitable material, a percussion cap tube 14, and a primer holder 15 carrying the primer 16. Aligned with the primer 16 is an axially displaceable firing pin 17 having a head 17a, the firing pin being continuously biased toward the primer 16 by a firing pin spring 18.

Arranged within the percussion cap tube 14 is the percussion cap 19. In order that same may be inserted 20 after the rest of the device is assembled, the screw ring 11 is adapted to receive a closure screw 20 which is screwed tightly into ring 11.

The detonator mechanism further comprises sealing discs 21 and 22 and sealing rings 23 and 24.

25 The winding stem 4a of the clock mechanism carries a windup handle 25 which is pivotally connected to the stem 4a and may thus occupy the position shown in FIGURE 1, or it may be folded down, the arrangement being, in practice, such that when the handle 25 is folded down, it is received in a depression formed in the cover 2 so as to lie flush with the rest of the cover.

Finally, the detonator mechanism includes the explosive charges 26 and 27 which may be briquetted to have the desired configuration which will enable them to 35 fit into the two compartments into which the interior of the housing 1 is divided by the web.

The device operates as follows:

The clock mechanism 4 is wound up by means of the handle 25, whereupon the clock mechanism starts to 40 run down. A weight is placed upon the mine; this weight will, in practice, be at least 1 kilogram and maximally about 100 kilograms. The weight presses down on the plate 9 which acts through the membrane 8 on the head 7c of the pivotally mounted lever 7. The locking projection 7b thereby frees the locking slide 4b of the clock mechanism so that when the clock mechanism has run down, the locking slide 4b springs back into the clock mechanism.

If the load resting on the plate 9 is removed, the firing 50 pin 17, acting under the influence of the spring 18, engages the blocking lug 7a, which is preferably formed with an angled cam surface, thereby raising the lever 7. This, in turn, frees the firing pin 17 which then, still under the influence of spring 18, strikes the primer 16 which, 55 in turn, ignites the percussion cap 19. The latter, in turn, sets off the primer charge 13 which ultimately detonates the main charge 26, 27.

The embodiment of FIGURES 3 and 4 differ from the above described embodiment of FIGURES 1 and 2 in 60 that the lever 7 and membrane 8 are replaced by a sliding head 30 made of plastic material and biased upwardly, as viewed in FIGURE 3, by a spring 31. The head 30 is axially displaceable within limits. The head 30 is provided with an integral locking projection 30b which coacts with the firing pin 17, and with a locking projection 30a cooperating with the slide element of the clock mechanism. The upper free end of the head 30 has a spherical configuration. The head is sealed by means of 65 a lip-type seal.

It will be seen from the above description of the two embodiments that a detonator according to the present

invention offers a number of advantageous characteristic features.

The head of the locking frame, i.e., the lever 7 or the head member 30, are so configured as to be engaged, centrally or substantially centrally, within a limited area which may even be point-shaped. This limited area can be engaged directly, as is the case with the spherical head member 30, or it may be engaged by the pressure plate 9. The latter may itself have a curved configuration. The element which actually blocks the forward movement of the firing pin, i.e., the blocking element constituted by parts 7a and 30b, respectively, is diametrically opposite the clock mechanism.

Furthermore, the diametral web will be seen to divide the housing into two compartments which accommodate the main charges. The web itself can be considered as having upper and lower layers; the upper layer supports the locking means of which at least a portion is located centrally, as well as the clock mechanism. The lower layer supports the primer charge assembly, located immediately below the clock mechanism, as well as the firing pin.

Furthermore, the web is provided with a ring-shaped portion which allows the head 7c of lever 7, or the head member 30, to move up and down, i.e., axially with respect to the housing.

Furthermore, the arrangement according to the present invention provides a generally rectangular recess in the web for receiving the clock mechanism, as well as the vertical and diametral recess for receiving the locking means. Moreover, the web arrangement makes it possible to provide the very conveniently configured stepped cylindrical recess for accommodating the primer charge assembly.

In practice, the housing can be made very simply by conventional manufacturing processes. This is also the case if the web is made integral with the housing. Furthermore, the lower cover can be made integral with the housing. The upper cover will be provided with suitable recesses for accommodating the winding stem of the clock mechanism, as well as for making possible the transmission of motion to the locking means. In the embodiment of FIGURES 1 and 2, the locking lever 7 does not itself project through the cover, but motion can nevertheless be imparted to the lever head 7c via the membrane 8, while in the embodiment of FIGURES 3 and 4, the locking head itself projects through the cover.

In practice, suitable sealing means are provided where necessary. These can be readily manufactured and assembled with the remaining structure. A particularly good seal against moisture, dirt, and the like, is provided with the arrangement of FIGURES 1 and 2 in which there is no physical opening through which the locking lever 7 passes.

In the embodiment of FIGURES 3 and 4, the blocking element 30b is arranged within a recess of the web and serves to prevent rotation of the head member 30.

Thus, the present invention provides a detonator which incorporates relatively few parts, each of which can easily be mass-produced at low cost, and which can be assembled in a very simple manner. In particular, the arrangement makes it possible to insert the primer assembly last. Furthermore, the detonator is very rugged, is well sealed against outside influences, and is fully operable even at extreme temperatures. Also, the over-all height of the device is very small. Yet another advantage is that the detonator operates very reliably, and can even be used in an inclined position.

A very marked advantage of the present invention is that the device operates even when the weight on the locking means is as low as one kilogram, because all that the force acting on the detonator is called upon to do is to counteract the effect of relatively weak spring means, whose low spring forces will effect a secure

"safety" despite the presence of but a small force on the locking means.

The detonator according to the present invention can be used as a weight-responsive contact or tread mine which, in contradistinction to other mines of this type, will explode only after the weight thereon has been removed.

It will be understood that the above description of the present invention is susceptible to various modifications, changes and adaptations, and the same are intended to be comprehended within the meaning and range of equivalents of the appended claims.

What is claimed is:

1. A detonator mechanism comprising, in combination:

- (a) a housing;
- (b) explosive charge means arranged within said housing;
- (c) a firing pin arranged within said housing and continuously biased from a rest position toward a firing position in which said explosive charge means are detonated;
- (d) weight-responsive locking means having a blocking element, said locking means being carried by said housing for movement between a depressed position in which said blocking element engages said firing pin to prevent movement of the latter from its rest position to its firing position, and a released position in which said blocking element is out of the path of movement of said firing pin, said locking means being arranged centrally of said housing; and
- (e) a clock mechanism arranged radially with respect to said locking means and having a radially movable slide element which is movable between an engaged position wherein said slide element engages said locking means to hold the same in its depressed position, thereby to prevent movement thereof to its released position, and a disengaged position wherein said slide element is free of said locking means, thereby to allow the same to move to its released position, said slide element being in its engaged position prior to running off of said clock mechanism and in its disengaged position after said clock mechanism has run off, in consequence of which said locking means will, upon the removal of a weight depressing the same, free said firing pin for movement toward its firing position.

2. A detonator mechanism as defined in claim 1 wherein said locking means has an engaging portion of limited surface area, and wherein said blocking element is diametrically opposite said slide element of said clock mechanism.

3. A detonator mechanism as defined in claim 1 wherein in said housing is provided with a generally diametrically arranged web which divides said housing into two compartments, said web supporting said locking means, said mechanism and said firing pin; said explosive charge means including explosive charges arranged in said compartments as well as a primer charge assembly which is also supported by said web and is arranged below said clock mechanism.

4. A detonator mechanism as defined in claim 3 wherein said locking means comprise an elongated lever one end of which is pivotally connected to an end of said web, the other end of said lever being located at the center of said web and being a head engageable by said sliding element of said clock mechanism, said blocking element being constituted by a projecting lug carried by said lever intermediate its ends.

5. A detonator mechanism as defined in claim 4 wherein in said housing is provided with a top cover which is provided with a recess which is in alignment with said head of said lever, said recess being closed off by a membrane, and said membrane carrying an actuating plate

so that pressure on said actuating plate is transmitted to said head of said lever via said membrane.

6. A detonator mechanism as defined in claim 3 wherein said locking means comprise a head member mounted for limited up and down movement and a spring continuously urging said head member to its up position, the latter constituting said released position of said locking means, said head member, interengaging with said slide element of said clock mechanism, and said blocking element of said head member being integral with the rest of said member and extending in the direction of the up and down movement.

7. A detonator mechanism as defined in claim 6 wherein said blocking member is arranged within a recess of said web and serves to prevent rotation of said head member.

8. A detonator mechanism as defined in claim 3 wherein said locking means have a substantially spherical portion located outside of said casing.

9. A detonator mechanism as defined in claim 3 wherein said housing is generally cylindrical, and wherein said web is integral with the remainder of said housing.

10. A detonator mechanism as defined in claim 1 wherein said housing is provided with a generally diametrically arranged web, said web having an upper layer and a lower layer, said locking means being arranged so that at least a portion thereof is positioned in the region of the center of said web in said upper layer thereof for up and down movement and said clock mechanism being arranged radially of said portion of said locking means and also in said upper layer of said web; said explosive charge means including a primer charge assembly supported by said lower layer of said web and located below said clock mechanism and said firing pin being located to move in the remainder of said lower layer of said web; said blocking element of said locking means extending down into said lower layer of said web when said locking means is in its depressed position.

11. A detonator mechanism as defined in claim 10 wherein said web is provided, at its center, with a ring-

like portion which receives said portion of said locking means.

5 12. A detonator mechanism as defined in claim 11 wherein said clock mechanism is received in a generally rectangular recess of said web, and wherein said web is provided with an opening through which extends said blocking element of said locking means.

10 13. A detonator mechanism as defined in claim 12 wherein said primer charge assembly is located within a cylindrical, stepped recess of said web arranged below said clock mechanism.

14. A detonator mechanism as defined in claim 10 wherein said housing is provided with top and bottom covers, said upper cover being provided with a central recess through which said locking means extend and with a further recess through which a winding stem for said clock mechanism extends.

15 15. A detonator mechanism as defined in claim 14, further comprising sealing means between said covers and said housing.

20 16. A detonator mechanism as defined in claim 14 wherein said central recess is closed off by a membrane.
